US0D1067829S

(12) **United States Design Patent** (10) Patent No.: **US D1,067,829 S**
(45) Date of Patent: ** Mar. 25, 2025

(54) **MOTORCYCLE**

(71) Applicant: **ZHEJIANG CFMOTO POWER CO., LTD.**, Hangzhou (CN)

(72) Inventors: **Chengyao Liang**, Hangzhou (CN); **Yanwei Lai**, Hangzhou (CN); **Liang Wu**, Hangzhou (CN); **Weikang Mao**, Hangzhou (CN)

(73) Assignee: **ZHEJIANG CFMOTO POWER CO., LTD.**, Hangzhou (CN)

(**) Term: **15 Years**

(21) Appl. No.: **29/891,017**

(22) Filed: **Apr. 28, 2023**

(30) **Foreign Application Priority Data**

Oct. 31, 2022 (CN) 202230721068.4

(51) LOC (15) Cl. **12-11**

(52) U.S. Cl.

USPC **D12/110**

CLAIM

The ornamental design for a motorcycle, as shown and described.

DESCRIPTION

FIG. 1 is a top-rear-right side perspective view of a motorcycle embodying our new design;

FIG. 2 is a top-front-left side perspective view thereof;

FIG. 3 is a front elevation view thereof;

FIG. 4 is a rear elevation view thereof;

FIG. 5 is a right side elevation view thereof;

FIG. 6 is a left side view thereof;

FIG. 7 is a top plan view thereof; and,

FIG. 8 is a bottom plan view thereof.

The broken lines depict portions of the motorcycle that form no part of the claimed design.

1 Claim, 8 Drawing Sheets
